(57) CLAIM

The ornamental design for T-shirt with attached two piece tie, as shown and described.

DESCRIPTION

FIG. 1 is a front elevation view of my new design of a T-shirt with attached two piece tie attached at an upper end thereof covered by a slip on knot according to one embodiment of my new design;

FIG. 2 is a left side elevation view of the design of FIG. 1 the right side being a mirror image, thereof;

FIG. 3 is a front elevation view of another embodiment of my new design showing the tie flipped upward as an illustration of its possible movement with respect to the shirt due to its attachment to the shirt at an upper end, where the shirt and tie are shown in a different color combination from that shown in FIG. 1;

FIG. 4 is a left side elevation view of the aspect of FIG. 3, the right side being a mirror image thereof, with the exception of the portion of the tie, which is flipped upward;

FIG. 5 is a front elevation view of another embodiment of my design showing a combined shirt and tie with another color combinational aspect of my new design, with stippling representative of a tinting of the material used for the ornamental design;

FIG. 6 is a left side elevation view of the aspect of FIG. 5, the right side being a mirror image thereof;

FIG. 7 is a front elevation view of another embodiment of my design showing a combined shirt and tie with another color combinational aspect of my new design;

FIG. 8 is a left side elevation view of the aspect of FIG. 7, the right side being a mirror image thereof;

FIG. 9 is a front elevation view of another embodiment of my design showing a combined shirt and tie with another color combinational aspect of my new design; and,

FIG. 10 is a left side elevation view of the aspect of FIG. 9, the right side being a mirror image thereof.

The broken lines, throughout the views showing stitching details and sleeve features, represent the portions of the T-shirt which form no part of the claimed design.
